US00D605305S

(12) **United States Design Patent**
Carter

(10) **Patent No.:** **US D605,305 S**
(45) **Date of Patent:** **** Dec. 1, 2009**

(54) **SCREENING DEVICE FOR SLEEP DISORDERS**

(75) Inventor: **James S. Carter**, Denver, CO (US)

(73) Assignee: **Sleep Holdings, LLC**, Denver, CO (US)

(**) Term: **14 Years**

(21) Appl. No.: **29/338,431**

(22) Filed: **Jun. 11, 2009**

(51) **LOC (9) Cl.** **24-01**

(52) **U.S. Cl.** **D24/231**

(58) **Field of Classification Search** **D24/107, D24/186, 188, 200, 231, 232; D14/160, D14/168, 217, 223, 299; D10/116; 600/26-28**
See application file for complete search history.

(57) **CLAIM**

The ornamental design for a screening device for sleep disorders, as shown and described.

DESCRIPTION

FIG. 1 is a first perspective view of a screening device for sleep disorders showing my new design;

FIG. 2 is a second perspective view thereof;

FIG. 3 is a first end elevational view thereof;

FIG. 4 is a second end elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a first perspective view of a screening device for sleep disorders showing an alternate embodiment of my new design;

FIG. 10 is a second perspective view of the alternate embodiment;

FIG. 11 is a first end elevational view of the alternate embodiment;

FIG. 12 is a second end elevational view of the alternate embodiment;

FIG. 13 is a right side elevational view of the alternate embodiment;

FIG. 14 is a left side elevational view of the alternate embodiment;

FIG. 15 is a top plan view of the alternate embodiment; and,

FIG. 16 is a bottom plan view of the alternate embodiment.

The dotted lines are intended to show features that are environmental only and form no part of the claimed design.
